UNITED STATES PATENT OFFICE.

GEORGE E. ADAMS, OF NEW BRITAIN, CONNECTICUT, ASSIGNOR TO FISK,
CLARK & FLAGG, OF NEW YORK, N. Y.

DESIGN FOR A BUCKLE.

SPECIFICATION forming part of Design No. 22,868, dated November 7, 1893.

Application filed April 13, 1893. Serial No. 470,251. Term of patent 7 years.

To all whom it may concern:

Be it known that I, GEORGE E. ADAMS, of New Britain, in the county of Hartford and State of Connecticut, have invented and produced a new and original Design for Buckles Adapted for Personal Wear, of which the following is a specification, reference being had to the accompanying drawings, and to the letters of reference marked thereon.

In said drawings: Figure 1 represents in front elevation a buckle embodying my present design. Fig. 2 is a sectional view illustrating the contour in cross section.

The essential features of this design will be seen to consist of a buckle having two oblong or ovoid openings B arranged parallel to each other, each surrounded by a narrow plain inner border F, an outer rounded or convex

border A and an intermediate beaded configuration E, this latter configuration consisting of a series of hemispheres arranged in line to form a border between the portions A and F. The tongue C is plain and has a loop opening D at the end.

The appearance of the buckle is highly ornamental and in accordance with the aesthetic tastes of this period, being designed more especially for personal wear on belts, &c.

Having thus described my invention, what I claim as new is—

The design for a buckle herein shown and described.

GEORGE E. ADAMS.
